FLOW-THROUGH TUBULAR STEAM
GENERATORViktor Juzi, Winterthur, Switzerland, assignor to
Sulzer Frères, Société Anonyme, Winterthur,
SwitzerlandApplication December 12, 1939, Serial No. 308,770
In Switzerland December 13, 1938

7 Claims. (Cl. 122—1)

The invention relates to a flow-through tubular steam generator having a tube system to which two separators are connected. The separator that carries off the injurious constituents from the working medium is arranged in the evaporation zone and the separator which effects a drying of the steam is located at the beginning of the superheating zone. The liquid discharge conduit being connected to and arranged to means operatively connected to a common temperature-responsive device actuated by the steam flowing to the second separator. The temperature-responsive device may be connected to the tube system between the separators. Advantageously, the first separator has a conduit provided with a throttling device which regulates the uniformity of flow therethrough, said conduit being connected to and arranged to pass a portion of the separated liquid to a low-pressure stage of the plant. The first separator is preferably provided with a second conduit having a control valve under the operation of the temperature responsive device. The second separator has a conduit for returning condensate to the feed water tank of the steam generator. The conduit for returning the condensate preferably is controlled by a valve actuated by the temperature responsive device.

The invention assures a proper de-salting of the working medium. It also prevents liquid particles from being carried along by the steam into the superheater or the points of consumption. Still another object of the invention comprises assuring a dependable control of the steam temperature. The invention will also permit proper cooperation between the de-salting of the working medium and the control of the boiler operation.

Fig. 1 of the accompanying drawings is a diagrammatic illustration of an arrangement of a tubular steam generator system embodying the invention.

Fig. 2 shows the details of the regulation of the discharge from the two separators.

Fig. 3 shows the details of the regulation of the quantities of steam taken from the steam generator.

The steam generator system illustrated in Fig. 1 comprises feed pump 1 which pumps feed liquid through the feed conduit 2 into the preheater 3. The preheated liquid, which under certain circumstances is already evaporated in small amount, then passes through the conduit 4 into the evaporator 5, in which a larger amount is evaporated so that only a smaller amount passes in liquid form into the first separator 6. A conduit 7 provided with a throttling device 8 of constant cross section conveys a portion of the separated liquid into the tube system 10 that is connected to a low pressure stage (not shown

in the drawings) of the steam power plant. Another portion of the liquid is led off through the conduit 11, which can be closed by means of the valve 12, into the feed tank 14. The portion of the liquid that is not led off from the separator 6 is mixed again with the steam and passes into the re-evaporator 16. At the end of the re-evaporator a slight superheating of the steam occurs. From the re-evaporator the steam flows through a thermostat (tube loop) 17 into the second separator 18. Liquid separated in each case can be led from the separator 18 into the feed tank 14 through the conduit 11 that can be closed by means of a valve 20. Only the vaporous portion of the working medium flows from the second separator into the superheater 21, in which it is brought to the temperature required for use and after flowing through the thermostat (tube loop) 22 passes through the conduit 23 into the power engine plant 26. After expansion of the steam in the engine plant 26 it is led through the conduit 27 into the heat exchanger 28, from which the condensate is conveyed into the feed tank 14 through the conduit 29 by the condensate pump 30. The heat evolving in the heat exchanger 28 from the high pressure working medium is transmitted to the working medium evolving from a low pressure stage of the steam plant.

The thermostat 17 first traversed by the steam influences by aid of the impulse sender 35 via the conduit 36 the servomotor 37 of the regulating valve 38. Furthermore, by the impulse sender 35 via the conduit 39 the regulating devices 41 of the furnace 42 can be influenced and via the conduit 43 the servomotor 44 of the valve 20 in the conduit 11 of the second separator can be influenced. Furthermore, via the conduit 44a the servomotor 45 of the valve 12 in the conduit 11 may be controlled. The thermostat 22 influences by aid of the impulse sender 46 via the conduit 47 the servomotor 48 of a flow-through valve 49 in the conduit 51. Through the conduit 51, in dependence on the superheating temperature, a larger or smaller amount of additional working medium is injected from the feed conduit 2 into the tube system of the steam generator at the point 52. The impulse sender 46 can furthermore influence via the conduit 53 the servomotor 54 of the flow-through valve 55 in the steam conduit 25 and can influence via the conduit 56 the servomotor 57 of the flow-through valve 60 in the by-pass conduit 61.

By aid of the pressure impulse sender 62 the servomotor 54 of the flow-through valve 55 is influenced in such a way that with increasing pressure in the conduit 61 an increased passage cross-section of the valve is adjusted and that with decreasing pressure a diminished passage

cross section of the valve is adjusted. If it should not be possible to prevent an increase of the pressure even when the valve 55 is completely opened, then the pressure impulse sender 62 influences also the servomotor 51 so that on further increase also the overflow valve 60 is opened and from the conduit 25 the steam can flow directly to the steam heat exchanger 28.

By aid of the two thermostats 17 and 22 the supply of feed medium through the feed conduit 2 and through the injection conduit 51 is regulated in such a way that the temperature of the steam flowing to the points of consumption keeps an unvarying equilibrium level. If, for example, the temperature should rise above the equilibrium level, then by aid of the thermostats a larger amount of feed liquid and injection liquid is adjusted so that the temperature is again lowered to the equilibrium level. Conversely, when the temperature falls the amount of feed liquid and of injection liquid is diminished and thereby the temperature is again raised to the equilibrium level.

The lengths of the tubes of the preheater 3, of the evaporator 5, of the re-evaporator 16 and of the superheater 21 are so dimensioned with respect to the heating by the furnace 42 and the supply of feed liquid through the conduit 2 and of injection liquid through the conduit 51 that the first separator 6 constantly receives a supply of working medium which still contains liquid, while the second separator 18 receives a supply of slightly superheated steam when operation is in equilibrium. The discharge from the first separator 6 is so adjusted by aid of the throttle 8 that not all the liquid can flow away. The flow-through valves 20 and 12 in the washing-out conduit 11 are closed by the thermostat 17 when from the re-evaporator there emerges steam with a definite superheating temperature. If a temperature is reached that is lower than a definite temperature limit at the exit from the re-evaporator (which, for example, can be about 30% above the saturated steam temperature), then by aid of the thermostat 17, of the impulse sender 35 and of the servomotors 44 and 45, the flow-through valves 20 or 12 are opened so that the excess water flowing through the tube system can again be led back to the feed tank 14. At the same time by the impulse sender 35 the cross section of the feed valve 38 is diminished to such an extent that the fall of temperature, which has caused the discharge of liquid from the two separators 6 and 18, is again eliminated and as a consequence the valves 20 and 12 are again closed. Accordingly, the flow displacements or pulsations which are caused in the tube system of through-flow steam generators in consequence of temperature regulating devices during operation are thereby compensated. The temperature-responsive devices can also be connected to the tube system before the first separator or behind the second separator.

The control apparatus illustrated in Figs. 2 and 3 comprises control members or valves 123, 160, 161, 162, 163, 132, 164, 165, 145, 166 and 167 and servomotors having cylinders 153, 131, 128, 125, 134, 142 and 139 which are supplied with a control liquid such as oil under pressure through conduits 168. The liquid is supplied from a pressure system not shown and a suitable pressure is maintained to operate the various pistons as will hereinafter be described. Each of the control members is connected to a discharge conduit 169 into which the liquid flows

as will hereinafter be described. The conduits 169 are preferably connected to a conduit system permitting the liquid to be returned to the pressure system which supplies the liquid to the conduits 168. Ordinarily, the liquid is discharged into the conduits 169 at normal atmospheric pressures.

The piston valve 218 (Fig. 2) of the valve 123 is loaded from below through the control pressure existing in conduit 36 and from above through spring 219. When the temperature of the steam flowing through tube loop 17 of the thermostat rises and the loop consequently gets longer, valve piston 218 is pushed downwards, compressing spring 219, and a connection is established between inlet conduit 168 and control conduit 36 through the openings 218a in control valve piston 218. In this way the control pressure in conduit 36 rises, so that piston 218 is again raised until the increased control pressure corresponds to the increased tension of the spring and consequently to the increased temperature. In the opposite case, if the temperature of the steam flowing through tube loop 17 falls and the loop consequently becomes shorter, the tension of spring 219 is reduced. The control pressure pushes piston 218 so far up that liquid can escape from conduit 36 to outlet conduit 169 as long as the reduced pressure in conduit 36 corresponds to the reduced temperature of the steam.

The liquid under pressure in conduit 36 acts on piston 220 of control member 163, in conduit 44a on piston 221 of control member 160, in conduit 43 on piston 222 of control member 161 and in conduit 39 on piston 223 of control member 162. Pistons 220—223 are consequently raised against the springs 224, 225, 226 or 227 when the liquid pressure in conduit 36 rises, and on the contrary the pistons move downward when the liquid pressure in conduit 36 becomes lower.

A rising of the pistons as described causes inlet conduits 168 to connect with the cylinders 125, 153, 131 and 128 and the liquid pressure therein to raise pistons 228, 229, 230 or 231 closing valves 12 and 20, opening valve 38, and closing damper 41a. By reason of the increased feed water admitted through valve 38 and the reduced air admitted through damper 41a, the temperature of the steam issuing from the steam generator is again brought back to normal. In addition to that, the quantity of liquid led away from the separators 6 and 18 is reduced.

When the temperature of steam in loop 17 falls, the piston 218 rises, connecting conduit 36 with conduit 169 and the liquid pressure acting on all the pistons 220—223 decreases causing them to descend. The corresponding cylinders 125, 153, 131 and 128 are connected to discharge conduits 169 so that the respective servomotor pistons 228—231 begin to descend, opening damper 41a, increasing the furnace combustion, closing valve 38, reducing the quantity of feed water, thus causing a proper adjustment of the steam temperature. At the same time valves 12 and 20 are opened, so that a greater quantity of water can be discharged from the separators.

Tube loop 22 of the thermostat (Fig. 3) acts on piston 171 of valve 132 due to changes in its length in consequence of changes in temperature with corresponding changes in the tension of spring 170. A rising temperature causes tub 22 to lengthen, so that spring 170 is more compressed and piston 171 is pressed downwards.

In this way liquid can pass from conduit 168 into conduit 56 through the opening 168a in piston 171. The pressure in conduit 56 rises until the piston 171 is again raised against spring 170 connecting conduit 56 with conduit 169 which discharges liquid, lowering the pressure.

When the temperature of the steam falls, loop 22 shortens and the tension in spring 170 is reduced. In this way piston 171 is raised, so that liquid flows into conduit 169 from conduit 56 until the desired regulation is established.

The result is therefore that with rising steam temperature the pressure in control conduit 56 rises, and in the contrary case with falling steam temperature the pressure in conduit 56 falls, with the result that, for any temperature of the steam flowing through loop 22, there is a corresponding liquid pressure in conduit 56.

The pressure responsive member 145 has a piston 173 which is connected to a plunger 174. This plunger is under the influence of the pressure in conduit 25, which pressure is transmitted to the cylinder of the plunger through conduit 175.

With rising steam pressure the plunger 174 and the piston 173 are raised. Liquid under pressure then flows from conduit 168, through opening 173a and into conduit 176, causing the pressure therein to rise. With falling steam pressure in conduit 25, the said piston and the plunger are forced downwards. From conduit 176 liquid can flow to conduit 169 until the reduced liquid pressure in conduit 176 corresponds to the reduced steam pressure in conduit 25.

By means of a hand-operated adjusting device 177, the spring 178 can be given more or less tension. By increasing the tension, the liquid pressure in conduit 176 is reduced; by reducing the spring tension, it is increased. The result is that the liquid pressures in conduit 176 rise or fall respectively with the steam pressures in conduit 25, and that, for adjusting to the proper value, the liquid pressures, corresponding to the steam pressures, can be variously adjusted by means of the hand-operated adjusting device 177.

The liquid pressure in conduits 56, 47, 53 and 56 acts on pistons 179, 180 and 181 of control members 164, 195 and 165. With rising liquid pressure, the pistons press against springs 182, 183 and 184 respectively. Consequently with rising liquid pressure or rising temperature of the steam flowing through tube loop 22, liquid can flow from the pressure-liquid system 168 into control conduits 185 and (under certain conditions) 186. On the other hand, liquid flows away from these conduits to drain system 169 if the liquid pressure or the steam temperature in tube loop 22 falls. The liquid pressures in conduits 176, 187 and 188 act upon pistons 189 and 190 of the control members 166 and 167 respectively, in such a way that, when the liquid pressure increases, they are raised against springs 191 and 192 respectively. In this way, with rising liquid pressure or rising steam pressure in conduit 25, liquid can enter from the pressure-liquid system 168 into control conduits 193 and 194 respectively. On the other hand, liquid flows away from conduits 193 and 194 respectively to drain system 169 if the liquid pressure or the steam pressure in conduit 25 falls.

Piston 181 of control member 165 is under the opposing action of the liquid pressure and the spring 184, and when service is normal, the pis-

ton stands in its upper position providing a constant connection between conduit 194 and conduit 166.

Piston 180 of control member 195 has annular surface 196 under the control pressure from conduit 56, a surface 197 under the liquid pressure in space 198, and a spring 183 opposing the liquid pressure. The piston remains during normal service so far down that there is always a connection between conduits 193 and 199. Only if the liquid pressure in conduit 56 exceeds a certain amount, and in consequence piston 180 is raised, liquid under pressure can pass from conduit 200 through space 201 and groove 202 into space 198. In this way the piston is pressed into its top position and there it remains. Then there is a permanent connection between conduits 199 and 200. The piston can be pressed downwards only by means of knob 203, and then the medium under pressure in space 198 flows through passage 204 into discharge conduit 169.

Servomotors 134, 139 and 142 have each a piston 205, 206, and 207, and these pistons are influenced on the annular surfaces 208, 209 and 210 by pressure from conduit 168 and on the piston surfaces 211, 212 and 213 by pressure from control conduits 185, 186 and 199. The pistons can be raised by hand by means of the adjusting devices 214, 215 and 216.

The apparatus shown in Fig. 3 works as follows under normal conditions:

If the temperature of the steam flowing through loop 22 rises, piston 179 of control member 164 is raised by the rising liquid pressure in conduits 56 and 47. From conduit 168 oil under pressure can pass through conduit 185 under the piston 205, so that the cone of valve 49 is raised. In this way the feed water introduced to the steam generator through conduit 51 is increased.

With reduction in temperature of the steam flowing through loop 22, the reduced control pressure in conduits 56 and 47 allows the piston to move downwards. In this way servomotor 134 is connected through conduit 185 to discharge conduit 169. Servomotor piston 205 moves downwards and the cross-section of valve 49 is decreased, and the water introduced to the steam generator through conduit 51 is decreased.

If the steam pressure in conduit 25 rises higher than it should, the liquid pressure in conduits 176, 187 and 188 also rises. Springs 191 and 192 are so strong relatively to each other that first of all the piston 190 is raised. In this way liquid can pass from conduit 168 under servomotor piston 206. The cone of valve 55 is raised, so that a greater quantity of steam can flow away through conduit 25 until the pressure has again been brought back to the proper amount.

If the correct steam pressure, however, can no longer be obtained when valve 55 is fully open, i. e. if the steam pressure in conduit 25 then still continues to rise, the piston 189 is also raised so high that oil under pressure can pass from conduit 168 through conduits 193 and 199 under servomotor piston 207. In this way the cone of valve 60 is raised, so that steam can flow from conduit 25 direct to the condenser through bypass 144 until the correct steam pressure has again been reached.

If the pressure in conduit 25 falls, in consequence of the falling liquid pressure, piston valve 189 is first of all pressed downwards again by spring 191 until servomotor 142 is connected

with discharge conduit 169 through conduits 199 and 193. Servomotor piston 207 then falls and reduces the cross-sectional area of flow of valve 60 until the pressure in conduit 51 has risen to its proper value.

If valve 60 has closed entirely without the correct pressure being reached, piston valve 190 also begins to descend, so that still another connection is made between servomotor 139 and discharge conduit 169 through conduits 186 and 194. Then, through the falling of servomotor piston 206, the cross-sectional area of flow of valve 55 is reduced, and this is effected until the correct pressure is restored in conduit 25.

Under abnormal conditions, i. e., if the temperature of the steam flowing through conduit 25 is too high or too low, the impulse sender 46 also takes part in the regulation.

Assuming that the temperature is too high, the liquid pressure in conduit 56 then becomes high and raises piston valve 180, thus creating a permanent connection between feed conduit 168 and conduit 199. Valve 57 is thus fully opened, so that all steam can flow away to the condenser from conduit 25 through conduit 144. The pressure in conduit 25 will at once fall, and thus the control pressure in conduits 176, 187 and 188 also falls and servomotor 139 is connected to discharge conduit 169 through conduits 186 and 217. In this way, when the temperature is too high, valve 60 is completely opened, and valve 55 completely closed, until, after a normal temperature has been restored, knob 203 and thereby also control piston 180 have been again pressed down by hand.

When the temperature is too low, the control pressure in conduits 56 and 53 becomes lower, so that piston valve 181 moves downwards, thus creating a permanent connection between servomotor 139 and discharge conduit 169 through conduits 186 and 217. Valve 55 is thus closed and the pressure in conduit 25 begins to rise. In this way valve 60 is raised, so that by letting off steam from conduit 25 through conduit 144 the correct pressure in conduit 25 is again restored.

After the temperature in conduit 25 has risen again to its normal value, piston 181 is raised, so that valve 55 is again controlled normally by the pressure, and steam can flow away through conduit 25.

I claim:

1. In a flow-through tubular steam generator which comprises a tube system including an evaporator and a superheater, a first separator connected in the evaporator, a conduit provided with a throttling device for carrying off injurious components of the feed water, a second conduit connected to the first separator for discharging liquid, a second separator for drying the steam connected at the beginning of the superheater, a conduit for the discharge of condensate from the second separator, a regulating valve in the second conduit and another regulating valve in the discharge conduit connected to the second separator, a device responsive to the temperature of fluid entering the second separator, and means operatively connecting the device responsive to temperature to each regulating valve.

2. A flow-through tubular steam generator according to claim 1 which comprises a plant having a low pressure stage, and means for trans-

mitting the heat of fluid discharged from the first separator through the conduit provided with a throttling device to the low pressure stage of the plant.

3. A flow-through tubular steam generator according to claim 1 which comprises a feed tank, and means for passing fluid discharged from the second separator to the feed tank of the steam generator.

4. In a flow-through tubular steam generator which comprises a tube system having an evaporator, a re-evaporator and a superheater, a first separator connected between the evaporator and the re-evaporator, a heat exchanger, means for passing liquid from the first separator to the heat exchanger, a valve controlled conduit for discharging liquid from the first separator, a device responsive to the temperature of fluid flowing from the re-evaporator arranged to operate the valve, whereby an unevaporated residue may be removed from the fluid passing through the evaporator, a second separator arranged to receive fluid from the re-evaporator and pass it to the superheater, a valve controlled conduit for discharging liquid from the second separator, a device responsive to the temperature of the fluid flowing from the re-evaporator arranged to actuate the valve in the conduit for discharging liquid from the second separator, and means for returning liquid discharged from the second separator to the evaporator.

5. A flow-through tubular steam generator according to claim 4 which comprises an engine arranged to receive superheated steam from the superheater, a valve controlling the admission of steam to the engine, and a device responsive to the temperature of the superheated steam arranged to actuate the valve.

6. A flow-through tubular steam generator according to claim 4 which comprises an engine, means for supplying the engine with superheated steam from the superheater, a conduit for discharging steam from the engine into the heat exchanger and in heat exchange relation to the liquid passed into the heat exchanger from the first evaporator, a by-pass conduit for passing steam from the superheater to the heat exchanger, a valve arranged to control the supply of superheated steam to the engine, a second valve arranged to control the flow of steam through the by-passed, and means responsive to the temperature of the superheated steam for controlling the action of the said valves.

7. A flow-through tubular steam generator according to claim 4 in which the evaporator, the first separator, the re-evaporator, the second separator and the superheater are in tubular series system comprising an engine arranged to receive superheated steam from the superheater, the heat exchanger being arranged to receive steam discharged from the engine, a pump and feed water tank, and a preheater, the liquid discharged from the second separator being passed into the feed tank, a valve arranged to control the passing of superheated steam into the engine, a valve-controlled by-pass for passing steam from the superheater around the engine to the heat exchanger, and a device responsive to the temperature of the superheated steam for controlling the action of the said valves.

CERTIFICATE OF CORRECTION.

Patent No. 2,321,390.

June 8, 1943.

VIKTOR JUZI.

It is hereby certified that error appears in the printed specification of the above numbered patent requiring correction as follows: Page 1, first column, line 9, strike out the words "being connected to and arranged to" and insert instead --of each separator has a regulating--; line 10, strike out the word --common--; and that the said Letters Patent should be read with this correction therein that the same may conform to the record of the case in the Patent Office.

Signed and sealed this 10th day of August, A. D. 1943.

(Seal)

Henry Van Arsdale,
Acting Commissioner of Patents.
